UNITED STATES PATENT OFFICE.

HERBERT L. KNIGHT, OF CLEVELAND, OHIO, ASSIGNOR TO THE WILLIAMS-ABBOTT ELECTRIC COMPANY, OF CLEVELAND, OHIO, A CORPORATION OF OHIO.

TRANSMITTER-ARM.

No. 823,336.

Specification of Letters Patent.

Patented June 12, 1906.

Application filed July 28, 1905. Serial No. 271,581.

To all whom it may concern:

Be it known that I, HERBERT L. KNIGHT, a citizen of the United States of America, and a resident of Cleveland, in the county of Cuyahoga and State of Ohio, have invented certain new and useful Improvements in Transmitter-Arms, of which the following is a specification, reference being had to the accompanying drawings, forming a part thereof.

10 My invention relates to improvements in supporting-arms for transmitters, and has for its object the construction of an arm which is cheap to manufacture, simple, servicable, and one which avoids certain disadvantages present in similar devices now upon the market.

15 My improvements are herein set forth as applied to a stamped transmitter-arm and bracket or base therefor, although not all of 20 said improvements are limited to this embodiment of my invention.

The device herein shown containing my improvements may be described as consisting of a bracket having two exterior ears 25 wherein the transmitter-arm, preferably of hollow or tubular form, is pivotally mounted at one end, while the other end carries the transmitter. This arm I may form of a single sheet-steel stamping or stampings, in 30 which case I interiorly reinforce it at its pivoted end in order to make the same rigid and improve the frictional engagement thereof. To aid in this function, I also mount within the ears of the bracket dished washers which 35 bear peripherally upon the arm at either side and hold it in adjusted position through pressure exerted by means of a transverse bolt. This bolt preferably is provided with a feather or key which engages the washers and prevents them from rotating with the arm.

40 The details of the construction just described will be more readily gathered by making reference to the accompanying drawings, setting forth a transmitter-arm constructed in accordance with my invention, 45 wherein—

Figure I is a view in side elevation, partially broken away, showing said transmitter-arm mounted within its bracket, together 50 with one of the engaging washers and the transverse pivot-bolt. Fig. II is a plan view,

and Fig. III a view in side elevation, of one of the dished washers. Fig. IV shows the transverse bolt with its binding-nuts. Fig. V is a view in vertical section on line 55, Fig. 55 I, showing the mounting of the several parts by means of the transverse bolt; and Fig. VI is a view in side elevation, also partially broken away, illustrating the transmitter-arm with attached transmitter removed from 60 its support.

Throughout the drawings the same character of reference is employed to designate similar parts in each of the several figures.

As stated above, the pivoted arm *a* preferably is formed of a single stamping of sheet-steel, the edges of which may be abutted or brought together along its under side, thus making a very simple, cheap, and presentable arm. As thus formed I may term the 70 transmitter-arm of my invention "semiseamless," and as ordinarily mounted no opposing edges are apparent to the user of the telephone. Its inner end is provided with circular flattened faces *a'*, through which extend 75 the openings *a''* for receiving the pivot-bolt. At the other end of said arm small ears or lugs *t'* are provided, whereby the transmitter *t* may be secured upon the arm. Adjacent to the pivotal opening *a''* is provided a 80 tubular reinforcing-piece *t''*, which surrounds the pivot-bolt and stays the rear side walls of the transmitter-arm *a*. This part enables me to secure the necessary or desired rigidity at this point, while making the transmitter- 85 arm of lighter gage material than would otherwise be possible with an arm formed of stampings and not interiorly reinforced. The base or bracket *b* likewise may be made of a single stamping of sheet-steel, the same having lateral ears *b'* for receiving the pivoted 90 transmitter-arm *a*. Transverse openings *b''* extend through the said ears and serve to accommodate the pivot-bolt *f*.

In order to hold the arm relatively rigid in 95 its positions of angular adjustment within its bracket, I have provided the dished washers *w w*, which are inserted within the ears *b'* of the bracket upon either side of the arm *a*. These washers bear upon said arm only adjacent to their outer periphery, thereby increasing the frictional effect upon the inter-

riorly-reinforced arm, which in consequence is quite rigid. The washers *w* are prevented from turning with the arm by means of the keys or feathers *f' f'*, struck up near either end 5 of the pivot-bolt *f*, the said bolt when assembling the structure readily passing through the openings *b'' w''*, and *a''*, respectively, provided in the ears of the bracket, the washers, and the transmitter-arm. The washers 10 are sufficiently dished, however, to suitably space the arm within the recessed ears *b'* of the bracket and position it centrally upon the bolt, so that it is free to move thereon as a pivot in a vertical plane. The keys or 15 feathers *f' f'* of the bolt, however, serve to secure the washers against rotation within the ears of the bracket.

Upon the threaded ends of the bolt *f* are screwed the nuts *n n*, which bear against the 20 ears *b'* of the base or bracket and which in turn engage the washers and force them tightly against the rear side portions *a'* of the arm *a*, thereby frictionally engaging said arm and retaining it in its positions of angular 25 adjustment within the bracket or base.

In the structure described are combined advantages present in both the solid and stamped transmitter-arms of the art. Thus the interior of the arm is left free to carry the 30 insulated conductors *c* to the transmitter, the open end at the rear of said arm being positioned adjacent to the back board or other mounting carrying the remaining conductors of the telephone instrument and permitting 35 the transmitter-conductors to be readily brought out to their terminals.

The arm as thus constructed of a single stamping of light sheet-steel is rearwardly made rigid by the short length of tube or reinforcing-piece *t''*. The washers *w* avoid the necessity for shaping the ears *b'* of the base or bracket in such manner as to directly engage the transmitter-arm, thus making the construction of said bracket simpler and 45 more sightly. Nevertheless the washers are securely held within the ears by the simple expedient of using a keyed or feathered bolt fitting correspondingly-shaped openings in the washers and embracing-ears. The use of 50 the pivot-bolt *f* permits the frictional engagement of the washers with the arm *a* to be adjusted as desired merely by tightening or loosening the nuts *n*, while the frictional engagement is secured adjacent to the periphery of these washers in a manner which avoids such cramping or binding of the arm as to prevent or impede its immediate adjustment as required by the user of the telephone.

As intimated above, certain features of my 60 invention are independent, and particularly the employment of the dished washers and coacting pivot-bolt are quite adaptable to constructions employing a solid or cast arm

and base, although I have herein set forth my invention in its preferred form— 65

I desire to secure by these Letters Patent the following:

1. The combination with a supporting-bracket or base portion, of a reinforced and semiseamless transmitter-arm pivotally mounted therein, and means for frictionally engaging said arm to retain it in its positions of angular adjustment with respect to the base; the said arm being formed of a single stamping of sheet metal shaped with its 75 edges abutting along its lower side, and having a reinforcing part interiorly inserted between the rear walls of said arm, substantially as set forth.

2. The combination with a supporting 80 bracket or base, of a stamped or tubular transmitter-arm pivotally mounted therein, a tubular reinforcing part rearwardly inserted in said stamped arm at its pivotal mounting, and interiorly engaging its walls adjacent to 85 said mounting and means for securing frictional engagement of the arm with its base or bracket, whereby it is securely held in its positions of adjustment, substantially as set forth. 90

3. In a supporting-arm for telephone-transmitters, the combination with a base or bracket, of a pivoted, vertically-adjustable arm mounted therein, stationarily-mounted dished washers provided at the pivotal 95 mounting of said arm to secure the desired frictional engagement, and a transverse pivot-bolt securely uniting the said parts, substantially as set forth.

4. In a supporting-arm for telephone-transmitters, the combination with a stamped base or bracket, of lateral ears provided thereon, a transmitter-arm pivotally mounted between the said ears, dished washers interposed between the said arm and engaging 105 ears of the bracket, and a binding pivot-bolt securely uniting the said parts and retaining the washers against rotation, substantially as set forth. 100

5. The combination with a base portion or 110 bracket having outwardly-extending ears, of a transmitter-arm pivotally mounted between the said ears, washers interposed at either side of said arm and between the ears of the bracket, and a transverse keyed or 115 feathered binding-bolt adapted to secure the washers against movement with respect to one of the members of the pivotal mounting, substantially as set forth.

6. In a supporting-arm for telephone-transmitters, the combination with a stamped base or bracket having outwardly-extending ears, of a tubular or stamped transmitter-arm pivotally mounted between the said ears, a reinforcing part rearwardly inserted 125 between the side walls of the arm adjacent to

the pivotal mounting, dished washers positioned at either side of the arm between the ears of the bracket, and a keyed or feathered binding-bolt securing the washers against rotation with respect to the pivotal ears of said bracket, substantially as set forth.

Signed at Cleveland, this 27th day of July,

1905, in the presence of two subscribing witnesses.

HERBERT L. KNIGHT.
